CLAIM

The ornamental design for a cart, as shown and described.

DESCRIPTION

FIG. 1 is a top-front perspective view of a cart according to a first embodiment of the claimed design.

FIG. 2 is a bottom-rear perspective view of the cart of FIG. 1.

FIG. 3 is a front view of the cart of FIG. 1.

FIG. 4 is a rear view of the cart of FIG. 1.

FIG. 5 is a left side view of the cart of FIG. 1.

FIG. 6 is a right side view of the cart of FIG. 1.

FIG. 7 is a top view of the cart of FIG. 1.

FIG. 8 is a bottom view of the cart of FIG. 1.

FIG. 9 is a top-front perspective view of a cart according to a second embodiment of the claimed design.

FIG. 10 is a bottom-rear perspective view of the cart of FIG. 9.

FIG. 11 is a front view of the cart of FIG. 9.

FIG. 12 is a rear view of the cart of FIG. 9.

FIG. 13 is a left side view of the cart of FIG. 9.

FIG. 14 is a right side view of the cart of FIG. 9.

FIG. 15 is a top view of the cart of FIG. 9; and,

FIG. 16 is a bottom view of the cart of FIG. 9.

The broken lines in the drawings illustrate portions of the cart that form no part of the claimed design.

The vent features shown in broken lines in FIGS. 2-6, 8, and

10-14 of the drawings form no part of the claimed design.

The cross-hatch shading shown in FIGS. 9-14 and 16 of the drawings at the cart base represents contrast in appearance.

The oblique line shading shown at the cart base in FIGS. 1-2 and 8 of the drawings represents translucency. The translucency forms part of the claim.
